CHECK DEVICE

George W. Gregory, South Orange, N. J., assignor to Shur-Chek Company, Inc., Fanwood, N. J.

Application February 2, 1933. Serial No. 654,796

5 Claims. (Cl. 40—2)

This invention relates to an improved check device which is designed to insure against loss of various articles that are separated in handling. The device is particularly adapted for use in laundries where pieces to be washed in different ways or materials to be re-assembled for ironing or for delivery.

The check devices are used in multiple to identify the separated articles of a batch and the device comprises a holder which receives a tag attached to the goods. The holder and tag have similar identifying marks such as numbers. The holder and tag have co-acting parts which are arranged to permit the attachment of a proper tag and insure the rejection of a tag not properly on the holder.

The tag and holder are so arranged that the proper tag allows the holder to be closed in holding position but the wrong tag will be in the path 20 of the latching portion of the holder and the latching portion can not be closed.

A drawing accompanies this specification which drawing illustrates a device embodying my invention. Figure 1 is a face view of a holder and tag assembled and secured to a tape. Figure 2 is a vertical cross-section on line 2—2 in Figure 1. Figure 3 is a face view of the holder with the tag removed and with the tape holding means in section. Figure 4 is a bottom view of Figure 3. Figure 5 is a face view of the tag detached.

The form of device shown in the drawing comprises a flat holder 10 which receives the tag 11 flatwise. The tag is provided with means for suspending articles which means may be a safety pin 12 one strand of which is held in the bead 13 bent over on the bottom of the tag. The holder is provided with a slide 14 which slides on the holder and is one means of holding the tag against the holder. The slide 14 slides on the holder freely and is held thereon by having its ends 15 bent around the back of the holder. In order to space the slide from the holder the holder is provided with flanges 16 at the sides. These flanges also assist in positioning the tag as the flanges are but slightly separated from the side edges of the tag. The insertion of the tag is also facilitated by the lip 17 struck up from the face of the holder 10 and placed at the proper point to properly position the tag in the holder.

The tag and holder have co-acting means for identification and to insure the assembly of the proper tag and holder. The form shown comprises embossed portions 18 and 19 on the holder and corresponding openings 20 and 21 in the tag. An unlimited number of such means is available

as the shape and position of the co-acting parts can be altered to a great extent. The form shown has the parts 18 and the hole 20 off-centre which insures against the tag being placed in the holder backwards.

The slide 14 is prevented from sliding from the holder by a lug or lugs 22 bent out at the back of the holder and in the path of the turned-over ends 15 of the slide.

I show the holder secured to a tape 23. The tape is passed doubled through a slit 24 in the holder and the loop 25 so formed receives a metal strip 26 which is wider than the slit 24. The ends of the strip 26 are bent over on the back of the holder. The strap or tape 23 is used to connect a number of holders 10 and thus various classes or kinds of articles such as articles of apparel in a laundry can be separated for various kinds of treatment and then re-assembled. This device insures their return to the same batch. The strap 23, or other holding means, and the tags are provided with a suitable mark for recognition or identification. I show numbers for this purpose.

In using the device, the tag is removed from the holder by raising the slide 14 and the tag is attached to the goods. After laundering or whatever else needs be done to the goods and they are to be returned to the batch, the tag is placed flatwise against the holder. The tag is easily positioned by engagement of its top edge with the lip 17 and its side edges with the flanges 16 and in this position the tag is easily placed with the holes or other means fitting into or over the co-acting positioning means on the holder. This is due to the fact that the means on the holder are spaced from the lip 17 and flanges 16 the same distance as are the means on the tag from the top and side edges of the tag.

When the tag is in place the slide 14 is slid down over the tag and holds the tag firmly in place. The tag when in place extends beyond the holder and the slide when in holding position is about central of the engaged part of the tag.

The parts are usually made of sheet metal and the holder particularly lends itself to easy manufacture as the lip 17, the flanges 16 and the stops 22 and slot 24 can all be made by one operation.

Various changes can be made in the form or proportions of the parts without departing from the scope of the invention.

I claim:—

1. A check device comprising a holder, a tag to lie flatwise against the holder, co-operating

- means for fitting the tag to the holder and a slide on the holder and adapted to confine or release the tag, and a suspension means on the tag.
2. A check device comprising a flat holder having identifying means thereon, a tag having means to fit the identifying means when the tag is placed flatwise on the holder and movable means for bearing on the tag to hold it in place against the holder.
10. 3. A check device comprising a flat holder having identifying means thereon, a tag having means to fit the identifying means when the tag is placed flatwise on the holder and a slide on the holder and adapted, when slid to locking position, to hold the tag against the holder.
15. 4. A check device comprising a sheet metal holder having a projection on one face, a slide 80
slidable on the holder and extending across the face thereof, a tag to fit flatwise against the face of the holder, the tag having a recess to receive the projection of the holder, the slide acting to confine the tag on the holder, and means on the tag for suspending articles.
5. A check device comprising a flat holder, a flat tag to fit flatwise against the holder, the holder and tag having co-acting means to cause the tag to assume a proper position, and a latching means spaced from the holder to engage a tag only when the tag is in proper position whereby a tag in improper position prevents the latching means passing to its closed position.
